UNITED STATES PATENT OFFICE.

MICHAEL JOSEPH STEIN, OF NEW YORK, N. Y.

IMPROVEMENT IN MACHINE FOR SEWING THE UPPERS TO THE SOLES OF BOOTS AND SHOES.

Specification forming part of Letters Patent No. 81,956, dated September 8, 1868.

To all whom it may concern:

Be it known that I, MICHAEL JOSEPH STEIN, of the city, county, and State of New York, have invented certain new and useful Improvements in Machinery for Sewing the Uppers to the Soles of Shoes and Boots; and I do hereby declare that the following is a full, clear, and exact description thereof, reference being had to the accompanying drawings making part of this specification, in which—

Figure 1 is a front elevation of the machine; Fig. 2, a side elevation; Fig. 3, a top view, Fig. 4 a side view, and Fig. 5 a bottom view, drawn full size, of the needle and cast-off, with their stocks connected; and Figs. 6 and 7, side and back elevations, drawn full size, of the rests for guiding the needle, represented in connection with the guide and the stock by which they are connected with the sewing mechanism; and Fig. 8, a section of the flue i^2 and thread-guides.

The same letters indicate like parts in all the figures.

My said invention relates to improvements on machinery for sewing the uppers to the soles of shoes and boots, described in Letters Patent of the United States granted to me, and bearing date the 9th day of May, 1865.

In the accompanying drawings, *a* represents a suitable frame, and *b* a movable table, on which the last-holder *c* rests and moves. This table is flat, and fitted to slide up and down on the vertical posts of the frame, and rests on four eccentric rollers, *d d d d*, arranged in pairs on two parallel shafts, *e e*, one near the front and the other near the back of the said table. The two eccentrics on the front shaft are connected, by joint links *f f*, with the two eccentrics on the rear shaft, so that when the front shaft is turned by a crank-handle or other suitable means, the two will turn in unison and set the table either higher or lower. The object of having the table adjustable in height is not only to suit shoes and lasts of different sizes, but also lasts of different curvature on the surface of the sole; as it is important that the needle should enter the leather of the sole at the bottom of the inner channel *g*, (see Fig. 6,) and come out at the angle of the outer channel *h*, and hence, as lasts of different curvature and height are put into the machine, the height of the table relatively to the sewing

mechanism must be so adjusted that the needle will enter the leather of the sole at the bottom of the inner channel and come out at the bottom or angle of the outer channel. In some instances the leather for the sole is not prepared with a groove or outer channel, such as represented in the drawings; but in such cases it is equally important that the needle should come out at a proper and like distance between the upper and lower surfaces. The last-holder *c* is a carriage, which rests on the surface of the table *b* so as to slide thereon in any direction required, and if desirable to relieve friction, it may be provided with rollers or small wheels. There is a hole made in the upper part of the last to fit a perpendicular stud, *j*, on the carriage, and when the last is turned sole upward, and forced down on this stud, a crutch, *k*, attached to the carriage, is then forced up by a screw against the toe-part of the last to brace and hold it firmly to the carriage. The whole of the sewing mechanism is mounted on a plate, *l*, the rear part of which is free to vibrate on the cam-shaft *m*, which is to be rotated in the direction of the arrow by any suitable motor. The forward end of this plate is guided in its movements up and down by the vertical side pieces of the frame; and it is suspended by a strap, *n*, to the periphery of a wheel, *o*, (see dotted lines in Fig. 1,) on a short shaft, *p*, provided with a crank-handle, *q*, which is held by a spring-catch, *r*, when the mechanism is to be held up when a shoe is to be removed and another substituted; but after a shoe and last-holder are put into the machine, the spring-catch *r* is pushed back to liberate the crank-handle *q* and permit the mechanism to rest by its weight on the sole of the boot or shoe to be sewed, that it may be free to follow the undulations thereof. A metal stock, *s*, (see Figs. 6 and 7,) is firmly secured to the plate *l*, and so formed, as represented, to extend down some distance below the under surface of the said plate. To the front part of this stock is hinged the upper end of an arm, *t*, and the inner face of the lower end of this arm forms the gauge *u*, against which the edge of the sole of the shoe to be sewed is pressed to guide it relatively to the needle as it is moved along by the feeder. (See Fig. 6.) This guide has a hole, *v*, through it for the passage of the point of the needle, and

another hole for the passage of a threaded stem, w , which projects from the stock s , and which is provided with a nut, x , by means of which the said gauge can be adjusted to the distance between the bottom of the channel g and the outer edge of the sole and the upper lying against it. There are two rests, y and z , fitted to slide vertically, one on each side of the said stock s . They are hinged at their upper ends to a cross-balance lever, a^1 , that is free to vibrate on a fulcrum-pin, b^1 , (see Fig. 7,) secured to the stock, so that when either of the rests rises or descends, the other must move to an equal extent in the opposite direction. The lower ends of these rests are formed to rest on the sole c^1 of the shoe to be sewed, so that it can slide under them, and as they rest on the sole, and are borne down by the weight of the plate l and the mechanism attached thereto, as the sole passes under them they will adapt themselves to the undulations of the sole, and as the needle, to be presently described, works midway between the two, and in the plane of their under surface in any position which they may assume in following the undulations of the sole, they effectually guide the needle so that it shall at all times be at the required elevation to enter the leather of the sole at the right place, which is the bottom of the inner channel g previously formed in the sole.

In the machine described in the patent heretofore granted to me there are two such rests mounted, and having a mode of operation such as above described, but both formed like the one y to enter, and, with their beveled edges, to bear against the bottom of the inner channel g of the sole, and to perform, in addition to the duty above described, the further offices of keeping the channel open and of resisting the pull of the needle in tightening the stitch during its back movement. So constructed, these rests presented the following difficulties: To admit of sewing around the usual curves at the heel and toe, the two rests require to be within a short distance of each other; for if placed too far apart the curved parts of the sole could not pass between them and the gauge, and when placed within a practical distance to avoid this difficulty, the one on the off side conflicts with the loop of the thread which connects the last formed stitch with the one which is being formed.

Two such instruments are indispensable to the guiding of the needle that its point may enter at the bottom of the channel in following the undulations of the sole; but for all other purposes one only is necessary. My present improvement consists in so forming the one, z , on the off side, that it shall stand back some distance from the bottom of the channel, but so that it shall rest on the surface of the sole. In this way it is made to answer the purpose of a balance to the one which rests against the bottom of the channel, that the point of the needle may be properly guided along to follow the undulations of the sole, while at the same time it avoids all conflict

with the loop of thread and admits of sewing along any curve, however small, and even around an angle, as in sewing square toe shoes.

The needle e^1 (see Figs. 4 and 5) is curved and made concentric on its inner concave face, and eccentric on its outer face, and therefore thicker toward the stock than toward the point. The object of this is manifold. In the first place, a needle of such form can be made of the required strength to act as an awl in piercing the leather. In the second place, the body of the needle in passing into the leather enlarges the hole the size required for the free passage of the needle-hook with its new loop of thread on the return motion, and this is effected without serious strain to the needle. In the third place, it avoids the straining of that part of the leather under which the needle passes, as no part of the leather can be strained which is above the needle, no part of its inner curved surface being at a less distance from the axis of vibration than the point, and hence the hole must be enlarged by the outer or eccentric surface of the needle, compressing the body of the leather. And, lastly, on the back motion of the needle the previously-formed loop of thread lies under the convex surface of the needle, and if the said loop should be gripped between the needle and the leather the back motion of the needle would fail to draw the stitch tight; but by making the needle with its outer surface eccentric, as it moves back the loop of thread is liberated, thereby permitting the stitch to be drawn tight. The needle is made flat and in the plane of motion on the side of the cast-off f^1 , and the cast-off is made of like form, that the faces of the two may work in contact, but without any interlocking tongue and groove, so that in tightening the stitch the needle may spring independently of the cast-off. The said cast-off is pointed that when it advances to cover the hook of the needle it may enter the leather easily to close the hook before it, (the hook,) on the back motion of the needle, reaches the loop which is to be cast off; and as this loop is at the time lying on the surface of the sole, and below the needle and cast-off, it is important that the cast-off should be brought to a point from the under side, otherwise in advancing to close the hook of the needle its point would be liable to catch onto the thread of the loop, particularly in sewing along the up-grade, as on one side along the shank of the sole from the heel part forward, where the surface of the sole inclines upward.

The needle e^1 is secured by having the rear end of its shank inserted in a hole in a stock, g^1 , (see Fig. 5,) and there secured by a temper-screw, h^1 , and the cast-off f^1 is in like manner secured to a similar stock, i^1 . The needle-stock and the cast-off stock are both mounted on a fulcrum-pin, j^1 , so as to vibrate thereon, and the inner faces of both the needle and the cast-off are concentric with this fulcrum-pin,

and their outer surfaces eccentric; and the contiguous faces of both are flat and move in contact one with the other. These two stocks g^1 and i^1 are received in a recess in one arm of a bent lever, k^1 , and connected therewith by the fulcrum-pin j^1 , and this bent lever k^1 is mounted in two hangers, $l^1 l^1$, the axis of vibration being back of the fulcrum-pin j^1 , and a little below the horizontal plane thereof, for a purpose to be presently described.

The in-and-out motions of the needle are derived from an eccentric, m^1 , on the shaft m . The rod n^1 from the eccentric is connected with one arm of a lever, o^1 , and the other arm of the said lever is connected with the needle-stock g^1 by a connecting-rod, p^1 , (see Fig. 4.) The motions of the cast-off are derived from a cam, q^1 , (see dotted lines in Fig. 2,) on the same shaft, which cam acts on one arm of a lever, r^1 , the other arm of which is connected with the stock i^1 of the cast-off by means of a connecting-rod, s^1 , (see Fig. 4,) a spring, t^1 , being employed to keep the said lever r^1 in contact with the periphery of the cam.

The periods of the relative motions of the needle and cast-off are determined by the form of the cam q^1 and its position relatively to the eccentric m^1 , and these are such, as represented, that the needle advances a certain distance while the cast-off stands still, to allow the loop to get out of the hook of the needle, and then the cast-off follows the needle in its forward motion to get between the loop so liberated and the hook, and that its point may enter the leather a short distance and there stop. The needle, in its continued forward motion, then passes through the leather until its hook is carried sufficiently through the material and the hole v in the outside gauge u to receive the thread, which is delivered in to the hook by the thread-carrier. The needle then moves back, drawing the thread through the material, and as soon as the hook is covered by the cast-off the two move together to the end of the back motion. The new loop of thread being inclosed by the cast-off in the hook of the needle, it is drawn through the previously-formed loop, which, by the continued back motion, is drawn in to tighten the previously-formed stitch.

As the needle passes in and through the leather its point has what may be termed a depressing motion—that is to say, as it advances its axis of vibration is depressed, and on the return motion lifted. To effect this motion the rear arm u^1 of the bent lever k^1 , before described, is hinged to the short arm of a lever, v^1 , (see Fig. 2,) that works on a fulcrum-pin, w^1 ; and the other arm is provided with a pin fitted to a cam-groove, w^1 , (see red lines in Fig. 2,) in the face of a cam-wheel, x^1 , on the shaft m , the said cam-groove being formed and located on the shaft, as represented in red lines in Fig. 2, so that the fulcrum-pin, on which the stocks of the needle and cast-off vibrate, will be depressed as the point of the needle is pass-

ing through the leather, and elevated as the needle is returning.

The thread f^2 passes through an eye in the thread-carrier y^1 , (see Figs. 6 and 7,) which vibrates on a fulcrum-pin, z^1 , on the gauge u , before described, through which the thread also passes; and the office of this carrier is to carry the thread so that it may be caught by the hook of the needle. To do this the carrier is vibrated to pass from one side of the needle under it and around to the other side, a short distance above the needle, as the needle is advancing, that the thread may enter the hook of the needle, and then it moves back again. To accomplish this the carrier is connected, by a rod, a^2 , with a vertical slide, b^2 , the upper end of which is formed with a double beveled projection, c^2 ; and to the side of the rod p^1 , which connects the stock g^1 of the needle with the lever o^1 , which operates it, there is hinged a spring-dog, d^2 , (see Fig. 6,) beveled on the upper and lower side, like the projection c^2 on the slide b^2 , which operates the thread-carrier, so that as the needle is being forced forward the spring-dog d^2 will depress the slide b^2 to vibrate the carrier, which is immediately drawn back by the tension of a spring, e^2 , that acts on the slide b^2 to lift it as soon as the spring-dog d^2 has passed. The thread f^2 , from a spool, g^2 , mounted on the plate l , passes over a guide, h^2 , and down through a flue, i^2 , attached to and so that it may move with the plate l , and around another guide, j^2 , at the lower end of this flue, and from this to and through the eye of the thread-carrier before described. The front plate of this flue i^2 is hinged, to give access to the thread. I prefer to make this flue of a gradual taper, and with the lower end considerably enlarged. To the lower end of this flue is suspended a lamp, k^2 , with a conical cap, l^2 , over the burner; this cap having two branch-pipes, m^2 —one to direct the heat into the flue i^2 to gradually heat the wax on the thread as it is descending, and the other to direct the heat to the eye of the thread-carrier y^1 to prevent the wax from clogging the said eye, which is a matter important to the practical working of the machine.

To adapt the machine to the sewing of welted shoes or boots there is combined with the sewing mechanism a welt-guide, n^2 , which consists of a mortise of sufficient size to receive and permit the welt, which is a strip of leather, o^2 , (see Fig. 1,) to pass through. A spring, p^2 , is attached to the arm of the guide to press the welt against the inner face of the guiding-mortise. The arm of this guide is placed by the side of the sewing mechanism and as near to the needle as the other parts of the machine will permit. It is hinged by its upper end to the stock s , so as to be self-adapting in position.

After the welt has been introduced and the first stitch taken the strip of welt will be drawn through the guide-mortise, as wanted, by the feeding motion applied to the sole. As it is

hinged to the machine, as before stated, when the machine is used for sewing turned shoes it is turned up out of the way.

In the patented machine before referred to, the feeding-pawl acted on the surface of the sole on the last, with its undulations, in the usual manner of a feeding-pawl, which resulted in making stitches of unusual length. When acting on a surface inclining upward back of the feeding-pawl, the feeder imparted a shorter motion than when acting on a level surface, and when acting against a reverse inclined surface it gave a greater feeding-motion than when acting on a level surface. This was a serious defect, which I have remedied by the present improvement, which consists in providing the feeding-pawl q^2 with a pin, r^2 , or equivalent projections from the sides thereof, not far from the place where the pawl is hinged to the lever s^2 , from which it receives its reciprocating motion. These projecting pins work in cam-like slots t^2 , (see Fig. 1,) in the lower end of a hanger, u^2 , the slots being of such form that when the pawl acts on an upward inclination, approaching, as at v^2 , (see Fig. 9,) it will act on the sole through the whole throw of its acting lever. When it acts on a level part of the sole, as at w^2 , in moving back and forth, the pins ride part of the way on the lower part of the cam-slot, so that the acting point of the pawl clears the sole for a part of the throw of the lever, and after the required range of lost motion has been attained the pawl then acts on the sole, and continues so to act, giving the required extent of motion to space the stitch; and in acting on a reversed inclined surface, as at x^2 , during the back and forward motions, the pins ride on the bottom of the slot for a greater portion of the throw of the lever, that there may be more lost motion. In this way, by the form of the cam-slots, the pawl is made to act on the sole through the whole of its range of motion, when acting up grade, to lose part of its motion in working on the level surface, and to lose still more when acting on a reversed or down grade, thereby spacing the stitches equally along the whole of the undulating surface of the sole. The upper end of the lever s^2 , which actuates the feeding-pawl q^2 , is hinged to a standard, y^2 , (see Fig. 3,) of the plate l , and this lever is connected by a rod, z^2 , with one arm of a lever, a^3 , (see Fig. 3,) which vibrates horizontally on a fulcrum-pin attached to the under side of the plate l , the other arm of the said lever being acted upon by a cam-groove, b^3 , (see Fig. 3,) on the shaft m , and as this lever receives at all times an equal range of motion, and it is desirable at times to vary the spacing of the stitches, the rod z^2 , instead of being hinged to the lever a^3 , passes through a hole in the said lever, and is provided with an adjusting-nut, c^3 , so that the lever a^3 gives the feeding motion to the pawl by striking the nut c^3 on the rod z^2 , and the feeding-pawl is drawn back by a spring, d^3 , so that the range of feed-

ing motion can be regulated by the set of the nut c^3 . It is also important to be able to adjust the position of the feeding-pawl relatively to the cam-slots t^2 , that the range of lost motion and the position of the point of the pawl relatively to the rest may be adjusted. To accomplish this the said cam-slots are formed in the lower end of the hanger u^2 , which is hinged by its upper end to the same standard, y^2 , to which the lever s^2 is hinged, and that end of the connecting-rod z^2 which is hinged to the lever s^2 , which operates the feeding-pawl, is slotted to embrace the hanger u^2 . Back of the hanger u^2 there is a set-screw, e^3 , which acts as a stop to the back motion of the hanger. When the spring d^3 pulls back the feeding-hand the hanger u^2 is drawn back, at the same time, by the back of the cam-slot striking the pin r^2 on the pawl until stopped by the set-screw e^3 , so that the range of the lost motion of the feeding-pawl can be adjusted by one set-screw, and the range of direct motion adjusted by the nut c^3 .

Having described and represented the mode of construction which I have tried in reducing to practical success my said invention of improvements in machinery for sewing soles to the uppers of shoes and boots which are to be turned after being sewed, and also the manner in which the machinery is adapted to the sewing of the upper and welt to an inner sole for boots and shoes which are not to be turned, I wish it to be understood that I do not limit my claim of invention to such specific mode of construction, as that may be changed without departing from the characteristic features which distinguish my said invention from all other things known.

I claim as my invention, and desire to secure by Letters Patent, in machinery for sewing shoes and boots—

1. In combination with the needle and the self-adapting rest, which is to rest and ride on the sole of the shoe or boot that is being sewed, and which is to bear against the bottom of the inner channel cut in the leather to resist the pull of the needle, a second rest, so formed that it shall rest and ride on the surface of the sole that in sewing it may not interfere with the loop of thread, the two being connected, and having a mode of operation in connection with the needle, substantially as herein described.

2. The curved needle, when made and mounted so that its inner curved surface is concentric with its axis of vibration and eccentric on its outer surface, substantially as and for the purpose specified.

3. The pointed cast-off, with its outer surface eccentric, in combination with the needle, the contiguous surfaces of the two being flat, and both being mounted so that they shall work in contact, substantially as and for the purpose set forth.

4. Attaching the lamp and its cap, and the flue through which the thread passes, to the

movable plate which carries the sewing-mechanism, substantially as described, that the means for heating and guiding the thread may be always in the same relative position, as set forth.

5. The feeding-pawl, with its projections, working in cam-formed recesses, or the equivalent thereof, having a like mode of operation, in combination with the movable table, on which the last-holder moves, or the equivalent thereof, by means of which combination the feeding-pawl spaces the stitches equally, notwithstanding it acts on the undulating surface of the sole, as described.

6. The welt-guide, substantially such as described, in combination with the mechanism, or the equivalent thereof, for guiding the sole on the last relatively to the sewing-mechanism, as described.

M. J. STEIN.
